DISMANTLING KEYBOLT FOR A PROPPING-UP AND SUPPORTING FRAMEWORK

BACKGROUND OF THE INVENTION

For making levelling flooring-slabs or other appreciably horizontal constructions, recourse is generally had to a framework of which at least the top part is provided with axially adjustable members, such as screwjacks, for supporting a mold form.

When the form is put into position, the frameworks are raised, for instance, by means of telescopic legs, up to an approximate height, then the screwjacks are regulated for suitably adjusting the position of the form.

To dismantle the construction it is necessary to reduce the height of the framework to a certain extent, so as then to be able to carry out a partial raising, particularly by means of hydraulic jacks, which enable the disengaging and withdrawing of telescopic legs, then the lowering of the framework. To carry out such operation, most frequently one acts on upper screwjacks, so as to lower the table in relation to the construction made. This operation is carried out by hand, so that the workmen are obliged to work at the top part of the framework, which entails considerable physical strain as well as the risking of more or less serious accidents owing to falling. Furthermore, when the top screwjack gets out of order, the positioning originally imparted to the form is altered and must then be readjusted.

SUMMARY OF THE INVENTION

The present invention overcomes these various disadvantages by creating a keybolt enabling the height of a framework to be sufficiently reduced by a simple and speedy operation carried out within easy human reach.

According to the invention, the keybolt, slipped transversally between a lower clamp of the vertical upright of a framework and a transversal pin engaged in an axially adjustable manner in a telescopic leg slidably mounted inside said upright, is formed by a U-shaped stirrup-piece comprising a semicylindrical core connecting two rigid parallel arms or wings each comprising a horizontal rectilinear edge cooperating with said clamp and a sloping edge converging towards said rectilinear edge to form a ramp cooperating with the removable pin traversing the telescopic leg.

BRIEF DESCRIPTION OF THE DRAWINGS

FIG. 1 is an elevation of a building and maintaining framework device fitted with a keybolt according to the invention;

FIG. 2 is a partial side elevation showing, on a larger scale, the keybolt, and

FIG. 3 is a section taken substantially along the line III—III of FIG. 2.

DETAILED DESCRIPTION OF THE INVENTION

FIG. 1 shows the applying of the keybolt, according to the invention, to a framework 1 shown, by way of example, in the form of a fixed scaffolding. This fixed scaffolding consists of a certain number of building members 2 and respectively formed by three tubes 3, 4 and 5 mutually assembled at one of their ends for extending in three planes, perpendicularly to one another. The holding of these tubes in their right angular relation is effected by angle-braces 6. The building elements 2, eight in number for instance, are mutually assembled at the free ends of their tubes 3, 4 and 5 to form a rigid framework of parallelepipedic shape comprising four vertical tubular uprights 3.

The fixed scaffolding thus made is completed by positioning, at the bottom ends of the four vertical uprights, of runway members 7, preferably removable, of telescopic legs 8, and at the top ends of said uprights of supporting members 9. The runway members 7 can be made by external or internal rollers whose spindles are mounted in bearings 10 made level with

the lower ends of the uprights 3. Each telescopic leg 8 includes a tube sliding on a corresponding vertical upright which is provided with a retaining member ensuring the axial locking of said tube in maximum penetration when the fixed scaffolding rests on the runway members. Each leg 8 has a series of transversal holes 8; FIG. 3, for receiving a pin 11, forming an adjustable abutment on which the corresponding end of the vertical tubular upright bears when the fixed scaffolding is placed in elevation in relation to the ground. Each supporting member 9 comprises a sleeve 12 fixed to the top part of the corresponding vertical tubular upright. The sleeve 12 is tapped for accommodating a threaded rod 13 whose top end is able to revolve on a catch 14 made integral with the core of a stirrup-piece 15 whose arms 16 rise vertically. The four stirrup-pieces 15 are oriented in pairs for supporting two parallel girders 17 on which the horizontal table 18 rests. Said table can be made in any suitable manner, particularly of sections 19 for holding shuttering or mold form 20 for making a horizontal construction or a levelling flooring-slab 21.

To operate the fixed scaffolding described above and raise the shuttering or mold form 20 up to the height corresponding to the building 21 to be effected, various methods can be put into operation. Generally, jacks 22, hydraulic for instance, are adapted on the bottom terminal parts of the tubular uprights, so that their rods 23 cooperate with shoes 24 able to be axially locked, in an adjustable manner, on the telescopic legs 8. After positioning the various jacks 22, a supply of fluid under pressure is controlled for causing the rods 23 to extend so that said rods by bearing on the shoe 24, ensure the raising of the fixed scaffolding by extension of the telescopic legs 8. When the approximate height is reached, the pins 11 are engaged in the telescopic legs 8 for forming abutments on which the vertical tubular uprights bear. The support members 9 are then adjusted by means of threaded rods 13 for imparting to the table the seating corresponding to the construction work 21 to be carried out. The operations for putting into effect, such as those described above, also comprise the fitting of the keybolt, according to the invention, between the pin 11 and clamp 25 integral with the corresponding bottom end of the vertical tubular upright of each telescopic leg 8.

According to FIGS. 2 and 3, the keybolt is formed by a U-shaped stirrup-piece 26 or bracket comprising a semicylindrical core or light portion 27 whose internal radius substantially corresponds to that of the telescopic legs 8. The core 27 connects two parallel rigid arms or wings 28 whose length is greater than the diameter of the legs 8. The arms 28 have aligned holes 29a, 29b, 29c, provided for receiving a locking pin 30 having a handle 31 secured to a chain or other flexible connection 32 with one of the arms or wings 28.

Each arm 28 has a rectilinear course 33, extending in the transversal plane defining one of the edges of the semicylindrical core or light 27, and a second course 34 sloped in a converging manner towards the course 33 and intercepting the second transversal plane defining the other edge of the semicylindrical core 27, but beyond the imaginary diametral plane of said core. The course 34 is made as a function of the length of the arms or wings 28 so as to have a same relatively slight slope and make ramps for cooperating with the terminal parts of the pin 11 projecting on either side of the telescopic leg 8.

After raising the framework 1 by means of the jacks 22, the various keybolts are inserted between the clamps 25 to rest by their ramps 34 on the pins 11 previously engaged in the corresponding holes of the telescopic legs 8. The engaging of each keybolt is done so that the core 27 is appreciably applied against the corresponding peripheral surface of the telescopic leg 8. The transversal locking of each keybolt is then assured by positioning the locking pin 30 in the holes 29a made in the arms or wings 28 for limiting, with the interior peripheral surface of the core 27, a passage section sufficient for the telescopic leg 8. In this position, in which the pins 11 cooperate with the beginning part of the sloped ramps 34, the keybolts 26 cannot be subjected to any accidental transversal or axial

displacement and, consequently, occupy a definite position which enables the supply to the jacks 22 to be reversed so as to make the framework 1 rest by the clamps 25 on the keybolts 26 bearing on the terminal parts of the pins 11.

When it is necessary to proceed to dismantle the building effected, the workmen in charge of this operation disengage the locking pins 30 of the keybolts 26 from the holes 29a then put them back again in the holes 29b. Each keybolt 26 is then moved in the direction of the arrow f_1 by repeated blows given level with the terminal parts of the arms or wings 18. The transversal sliding of each keybolt 26 is easily done between the clamp 25 and the pin 11 owing to the presence of the ramps 34 whose slope is chosen for preventing a sudden unexpected disengaging. As the keybolts 26 are progressively withdrawn, the sloped ramps 34 cause the progressive lowering of the framework which is thus subjected to a slight downward vertical displacement for the removal, without sudden movement, of the mold form 20 of the building 21. The transversal displacement of each keybolt is normally carried out up to the moment when the locking keybolt 30, engaged in the holes 29b, is brought into contact with the telescopic leg 8.

In addition to the abutment function limiting the amplitude of the transversal sliding of the keybolts 26 during dismantling, it should be noticed that the locking pins 30 also form safety members opposing any risk of complete disengagement, which might have the effect of subjecting the framework to an abrupt fall on to the pins 11.

According to the applications, the first transversal sliding stage of each pin can be followed by an identical stage by disengaging the locking pin 30 from the holes 29b for reintroduction in the holes 29c. This gives the benefit of an additional transversal sliding amplitude enabling a more considerable lowering vertical movement of the framework.

When the transversal displacement of the various keybolts is done, the jacks 22 are supplied with pressure fluid for extending piston rods 23 raising the framework to an extent just sufficient for relieving the various pins 11 which can thus be disengaged from the telescopic legs 8. The complete lowering of the propping-up framework is then controlled by means of the jacks 22, contingently combined with the progressive displacement of the pins 11 in relation to the telescopic legs 8, in the case where it is necessary to provide safety elements capable of avoiding failures of jacks 22.

As can be seen from the foregoing, the complete lowering of the framework is thus obtained without disturbing the seating of the mold form support and solely by means of simple operations carried out without danger at a height within easy human

reach.

I claim:

1. A keybolt for propping a vertically extensible framework and enabling selective lowering thereof for dismantling thereof, comprising a rigid U-shaped bracket for straddling a lower leg of the framework and supported by a pin in said leg to constitute a stirrup for supporting an upper leg telescoped on the lower leg, said bracket including a bight portion connecting two parallel arms each having a horizontal rectilinear upper edge and a lower edge inclined upwardly from said bight portion toward the upper edge, said upper edges constituting the support stirrup and said lower edges constituting a ramp engageable with the supporting pin for lowering said stirrup when the bracket is moved transversely of the leg and means spanning said arms to limit transverse movement of the bracket.
- 10 2. A keybolt according to claim 1 wherein said arms are of a length substantially greater than the transverse dimensions of the framework leg to be straddled, said means comprising a pair of aligned holes in said arms, said holes being spaced from said bight portion a distance substantially equal to the transverse dimensions of the leg and a retainer removably inserted in said pair of holes to retain said bracket in full supporting position or permit transverse movement of said bracket relative to the leg to enable lowering of said stirrup as the ramp edges slide on the leg supported pin.
- 20 3. A keybolt according to claim 2 wherein said arms are of a length substantially greater than the transverse dimensions of the framework leg to be straddled, said arms having a plurality of said pairs of aligned holes spaced longitudinally of said arms whereby said retainer may be removably inserted selectively in a pair of holes to retain said bracket in full supporting position or permit limited transverse movement of said bracket relative to the leg to enable an incremental lowering of said stirrup as the ramp edges slide on the leg supported pin.
- 30 4. A keybolt according to claim 3 wherein there are three of said pairs of holes.
- 35 5. A keybolt according to claim 2 comprising a flexible connector securing said retainer to said bracket.
- 40 6. A keybolt according to claim 1 wherein said bight portion is semicircular and has an internal radius substantially equal to the radius of the framework leg.
- 45 7. A keybolt according to claim 1 wherein said bight portion is semicylindrical with the ends thereof contiguous with said arms at a diametrically disposed plane, said inclined lower edges of said arms intersecting the lower edge of said bight portion beyond said plane.
